FLUID LIFT PUMP

Alexander D. Murphree, Humble, Tex., assignor
of one-half to M. Manning, Harris County, Tex.

Application June 11, 1936, Serial No. 84,619

7 Claims. (Cl. 103—233)

This invention relates to a fluid lift pump, and has particular relation to that type of pump which is adapted to operate in a well, such as an oil well, and to utilize an operating fluid such as air or gas under pressure to expel the well liquid from the well.

Another object of the invention is to provide a pump of the character described embodying a tubing which is extended down through the well casing and is provided with a seal between said tubing and casing whereby the operating fluid will be excluded from the producing stratum with upwardly opening valves controlling the inflow of liquid into the tubing and said tubing being provided with a port into the casing between the valves and above said seal whereby the liquid to be pumped may rise in the casing outside of said tubing to the normal liquid level, said pump also including a pressure line for the operating fluid located within the tubing and equipped with spaced ejector valve mechanisms for controlling the application of the operating fluid at different levels to the liquid being expelled through the tubing.

The invention also comprehends a novel type of ejector valve mechanism incorporated into the pressure line for the operating fluid.

With the above and other objects in view the invention has particular relation to certain novel features of construction, operation, and arrangement of parts, an example of which is given in this specification and illustrated in the accompanying drawing, wherein:

Figure 1 shows a vertical sectional view of the upper end of the pump.

Figure 2 shows a vertical sectional view of the lower end thereof.

Figure 3 shows a sectional view of the ejector valve taken on the line 3—3 of Figure 4.

Figure 4 shows an enlarged vertical sectional view of an ejector valve mechanism and Figure 5 shows a side elevation partly in section of the pump.

Referring now more particularly to the drawing wherein like numerals of reference designate similar parts in each of the figures, the numeral 1 designates a well casing to the upper end of which casing head 2 is attached the said casing head having the usual outflow line 3 for the relief of gas or liquid from the casing. The outflow line 3 may be controlled by the conventional valve not shown.

Beneath the casing and extended down into the producing formation there is a tubular liner 4, usually formed into a screen through which

the inflowing liquid may pass. Between the upper end of the liner and the lower end of the casing there is a suitable packer as 6 to form a fluid tight joint.

Within the casing is the tubing 7 which extends up through and above the casing head, and fitted closely around the tubing and secured on the casing head there is a suitable gland as 8. Between the tubing and the upper end of the liner 4 there is an annular packer 9 forming a fluid tight joint between them and beneath said packer the tubing is reduced and extended down into the said screen and is provided with a valve seat 10 whereon is located the upwardly opening standing valve 11 which permits the inflow of liquid upwardly through the tubing but prevents the back flow of the liquid. Above the packer 9 the tubing has the ports 12 leading into the casing and above said ports is provided with a back pressure valve seat 13 which is controlled by the upwardly opening back pressure valve 14.

Above the gland 8, the tubing is provided with a discharge pipe 15 and the upper end of the tubing is closed by the closure cap 16 which contains a stuffing box 17 through which the line 18 is closely fitted and said line extends down into the tubing the required distance. Fastened on to the lower end of the line 18 is an enlarged nozzle 19 having the upwardly directed nozzle openings 20.

Incorporated into the line 18 at spaced intervals therealong are ejector valve mechanisms indicated generally by the numeral 21. Each ejector valve mechanism embodies an outer housing 22, whose upper and lower ends are reduced and outwardly threaded for connection to adjacent sections of the line 18. Fitted downwardly through each housing 21 are the tubular valve casings 23, 23 which are preferably screwed into said housing and the lower ends of these casings are equipped with the annular valve seats 24 which are screwed into said valve casings. Leading out laterally from the axial passageway 25 through each housing 22 are the ducts 26, 26 which lead on through said seats 24 and the seats 24 are controlled by the upwardly opening valves 27, 27 located within the casings 23, 23. Each valve 27 has an upstanding stem 28 which works in a corresponding tubular guide 29 which is threaded into the upper end of the corresponding casing 23. Each guide has an external shoulder 30 thereon and surrounding the guide and confined between the valve and said shoulder is the coil spring 31 which normally acts to hold the corresponding valve 27 seated. The guide may be 55

adjusted to regulate the compression of the spring 31 and may be locked in adjusted position by means of a lock nut 32 screwed thereon. Above each shoulder 30 the corresponding guide has the 5 inlet opening 33 and the operating fluid passes through the passageway 25, the ducts 26, past the valves 27 up through the casings 23 and then in through the openings 33 and on up through the guides 29 into the liquid in the tubing 7 above. 10 The compression of the springs 31 should be so regulated that those of any particular ejector valve mechanism will have a slightly greater compression or resistance against the valves 27 than those of the next ejector valve mechanism 15 beneath.

In operation, the pump may be located in the well at such depth that the upper ejector valve mechanism will be submerged. The well liquid entering through the standing valve 11 will pass 20 upwardly both into the tubing 7 as well as into the casing 1 and will reach a common level in the tubing and casing. It is to be noted that the outside diameter of the housing 22 is substantially the same as the inside diameter of the 25 tubing 7 so that the housing will fit closely in the tubing, said housing having the external vertical channels 22a through which the liquid will pass freely up through the tubing 7 past the housing. An operating fluid such as air or gas under pressure 30 is now forced downwardly through the line 18 and it will operate to lift the valves 21 of the upper ejector valve mechanism first for the reason that these valves sustain a less load of the liquid column than the valves of the ejector valve 35 mechanisms beneath. The column of liquid above the upper ejector valve will be set in motion upwardly through the tubing 7 above by the operating fluid, relieving the valves 21 of the load of said column of liquid and also relieving the valves 40 27 of the ejector valve mechanism beneath of a similar load whereupon these last mentioned valves 27 will open and the springs 31 will close the valves 27 above to the end that the ejector valve mechanisms will be opened from above 45 downwardly, and the upward movement of the column of liquid continued.

Thereafter, under normal operating conditions, when the lower ejector valve mechanism is set in operation it will thereafter continue to operate 50 during the normal operation of the pump, the valves above remaining closed.

As the liquid is ejected from the discharge line 55 15, the pressure on the column of liquid in the casing 1 will be correspondingly relieved and this liquid will flow back through the ports 12 into the tubing 7 and up through the valve 14 and at the same time additional liquid will flow in from the producing stratum through the standing valve 11 up into the casing 1 to take the place of that 60 relieved from the casing.

Excess pressure of the operating liquid passing 65 60 downwardly through the line 18 not required to operate the valves 27 will pass on down and will be ejected outwardly and upwardly into the column of liquid in the tubing 7 through the nozzle openings 20 and the operating fluid ejected through the openings 21 may be sufficient to continue the upward movement of the column of liquid moving upwardly through the tubing 7, the 70 valves 27 above remaining closed.

The drawing and description disclose what is 75 now considered to be a preferred form of the invention by way of illustration only, while the broad principle of the invention will be defined by the appended claims.

What I claim is:

1. A fluid lift pump comprising a well casing, a tubing therein extended beneath the casing, means adjacent the lower end of the casing for forming a seal between the casing and tubing, the tubing having a port leading into the casing above the seal, an inlet valve beneath the port for controlling the inflow of liquid into the tubing, a line extended into the tubing for the conduct of an operating fluid, under pressure, and ejector valves incorporated into said line at different levels whereby the operating fluid may be discharged into the liquid, in the tubing, to discharge said liquid. 5

2. A fluid lift pump comprising a well casing, a tubing therein extended beneath the casing, upper and lower seals between the tubing and the casing, the tubing having a port leading into the casing above the lower seal, an upwardly opening inlet valve above the port for controlling the inflow of liquid into the tubing, a line extended into the tubing for the conduct of an operating fluid under pressure, ejector valves incorporated into the line at different levels whereby the operating fluid may be discharged into the liquid in the 20 25 tubing to discharge said liquid. 25

3. A fluid lift pump comprising a well casing, a tubing therein extended beneath the casing, upper and lower seals between the tubing and the casing, the tubing having a port leading into the 30 casing above the lower seal, an upwardly opening inlet valve above the port for controlling the inflow of liquid into the tubing, a line extended into the tubing for the conduct of an operating fluid under pressure, ejector valves incorporated 35 into the line at different levels whereby the operating fluid may be discharged into the liquid in the tubing to discharge said liquid, and an outflow line leading from the tubing above the upper seal. 40

4. A fluid lift pump comprising a well casing, a tubing therein extended beneath the casing, upper and lower seals between the tubing and casing, the tubing having a port leading into the casing above the lower seal, an upwardly opening inlet 45 valve in the tubing above said port, an upwardly opening inlet valve in the tubing beneath said port, a line for the conduct of an operating fluid under pressure extended into the tubing, ejector valves incorporated into said line at different 50 levels through which the operating fluid may be discharged into the liquid in the tubing. 50

5. A fluid lift pump comprising a well casing, a tubing therein extended beneath the casing, upper and lower seals between the tubing and casing, 55 the tubing having a port leading into the casing above the lower seal, an upwardly opening inlet valve in the tubing above said port, an upwardly opening inlet valve in the tubing beneath said port, a line for the conduct of an operating fluid 60 under pressure extended into the tubing, ejector valves incorporated into said line at different levels through which the operating fluid may be discharged into the liquid in the tubing, and a nozzle having a discharge port on the line beneath 65 the lowermost ejector valve. 65

6. A fluid lift pump comprising a pipe in a well, a tubing therein, upper and lower seals between the pipe and tubing adjacent the upper and lower ends respectively of the pipe, said tubing having a port leading into the pipe above the lower seal and having a discharge outlet above the upper seal, inlet valves for controlling the inflow of liquid into the tubing, one of said valves being located above and the other beneath said port, a 70 75

line extended into the tubing for the conduct of an operating fluid under pressure, ejector valve mechanisms incorporated into said line at different levels whereby operating fluid may be discharged into the liquid in the tubing, each ejector valve mechanism including a valve and a yieldable member for normally holding the valve closed, the yieldable member of each valve mechanism exerting a greater pressure against the corresponding valve than that of the ejector valve mechanism beneath.

7. In a fluid lift pump, an ejector valve mechanism comprising a housing having a passageway therethrough, a valve casing therein having a seat, a valve on said seat, a tubular guide in the casing, a yieldable member between the guide and valve normally holding the valve closed, said housing having a duct leading from said passageway through said seat and continuing through the casing and guide. 5
